US0D1026222S

(12) **United States Design Patent** (10) **Patent No.:** **US D1,026,222 S**
(45) **Date of Patent:** **** May 7, 2024**

(54) **NEEDLE CATHETER PLACEMENT DEVICE**

(71) Applicant: **Angie Technologies Ltd.**, Tel Aviv (IL)

(72) Inventor: **Israel Gershi**, Tel Aviv (IL)

(73) Assignee: **Angie Technologies Ltd.**, Tel Aviv (IL)

(**) Term: **15 Years**

(21) Appl. No.: **29/889,660**

(22) Filed: **Apr. 14, 2023**

Related U.S. Application Data

(63) Continuation of application No. 29/783,275, filed on May 12, 2021, now Pat. No. Des. 987,075.

(51) **LOC (14) Cl.** **24-02**

CLAIM

The ornamental design for a needle catheter placement device, as shown and described.

DESCRIPTION

FIG. 1 is a top perspective view of a needle catheter placement device showing the claimed design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dashed broken lines in the figures show portions of the needle catheter placement device that form no part of the claimed design.

The dot-dash broken lines in the figures show boundaries that form no part of the claimed design.

The figures include shading to illustrate illumination. Color forms no part of the claimed design.

1 Claim, 6 Drawing Sheets
